J. WALDHEIM

TYPEWRITING MACHINE

Original Filed Aug. 26, 1921

UNITED STATES PATENT OFFICE.

JOHN WALDHEIM, OF ELIZABETH, NEW JERSEY, ASSIGNOR TO UNDERWOOD TYPE-WRITER COMPANY, OF NEW YORK, N. Y., A CORPORATION OF DELAWARE.

TYPEWRITING MACHINE.

Application filed August 26, 1921, Serial No. 495,679. Renewed September 11, 1924.

To all whom it may concern:

Be it known that I, JOHN WALDHEIM, a citizen of the United States, residing in Elizabeth, in the county of Union and State 5 of New Jersey, have invented certain new and useful Improvements in Typewriting Machines, of which the following is a specification.

This invention relates to continuous billing typewriting machines, one form of which is shown in the patent to Wernery and Smith, No. 1,132,055, dated March 16, 1915, and in which a pack of continuous webs may be fed from a source of supply over a rearward extension 10 of the typewriter-carriage and between interleaved carbon-sheets of a carbon-displacing carriage, the sheets being led around the platen to the printing point. The webs are usually provided with printed forms or bill heads disposed in sets lengthwise of the pack, the forms being filled in by the typewriting machine. After a set of forms has been typed, the carbons are first shifted or displaced prior to severing or 15 tearing off a set of printed forms. To enable this to be done, the platen may be raised to a position to allow the straightening out of the webs, so that the carbon may be freely displaced by pushing the carbon-carriage rearwardly, thus taking the carbons to a 20 new set of forms, and at the same time the webs may be drawn forwardly to a stop to engage the length of said forms. After this is done, the platen may be lowered to its 25 typing position, and the printed forms may then be severed by a suitable knife.

The adjacent webs of the pack are joined to each other by folds at their side edges. The folded edges may be perforated so that 30 the various forms may be readily separated from each other, after severing a set of forms from the pack. The perforations, however, leave a ragged edge which detracts from the general appearance of the bill. Due to this fact, the users of the 35 fan-fold webs sometimes trim the side edges of the pack before introducing it into the machine. This is objectionable, however, since the separate sheets tend to creep relatively to each other in the operation of 40 feeding them around the platen while typing the forms. It is, therefore, desirable to trim the side edges of the webs after they

have been inserted in the machine, and thus prevent cumulative creeping of the sheets 55 relatively to each othr.

In my pending application, No. 448,047, filed February 26, 1921, I have provided for this purpose two relatively fixed cutters, one at each side of the web, and mounted on the 60 carbon-carriage, so that the edges may be trimmed by said cutters during a carbon-displacing operation.

An object of this invention is to provide 65 rotatable cutters on the carbon-carriage to trim the edges of the web, said cutters being geared to a rack to be rotated as they move rearwardly with the carbon-carriage, the peripheral speed of each cutter being greater than its bodily movement. 70

Another object of the invention is to provide 75 guiding means which may comprise a pair of flat bars, to prevent the edges of the web from leaving the cutters while said edges are being trimmed.

Other features and advantages will hereinafter appear.

In the accompanying drawings,

Figure 1 is a sectional side view of a typewriter-carriage and the rearward extension thereof upon which the carbon-carriage travels back and forth relatively to the platen. 80

Figure 2 is a sectional front view, on a somewhat reduced scale, showing the relation 85 between the pack of webs and the cutters, the section being taken on the line 2-2 of Figure 1.

Figure 3 is a fragmentary top plan view 90 of the rear part of Figure 1.

Figure 4 is a perspective view as seen from the upper forward right-hand corner of the machine and shows the driving mechanism for the cutters.

Figure 5 is a detail view of the gearing 95 for the cutters, showing the driving rack disposed to rotate each cutter in an opposite direction to that in Figure 1.

Figure 6 is a slightly modified form of the 100 invention, in which a single set of cutters is used.

Type-bars 10 may swing upwardly and rearwardly to print against the front face of a platen 11, mounted in a carriage 12 to travel back and forth on the main frame 10 (not shown) of an Underwood typewriting

machine. To the carriage 12 is connected a rearward extension or table 13 comprising a front bar 14 and a rear bar 15 connected to each other by side bars 16, the rear bar 5 having upwardly-extending arms 17 to support a guide-bar 18, over which a continuous pack 20 of webs or work-sheets 21 may be fed from any suitable source of supply. The webs are led forwardly to a guide-bar 22 on 10 the carriage and then downwardly around the platen 11 to the printing point at the front of the platen. The webs are then guided upwardly behind the usual knife 23, by which portions thereof may be severed 15 from the pack 20. The separate plies or webs of the pack are each connected to its adjacent one by folds 24 (Figure 4), and the webs are interleaved in the usual way by carbon-sheets 25 secured to carbon-carrying 20 bars 26 on a carbon-carriage 27. The carbon-carriage is mounted on tracks 28 secured to the side bars 16 of the rearward extension, so that it may move freely forwardly with the webs as they are fed around the platen 25 and be moved rearwardly to shift the carbons to fresh portions of the webs, as hereinafter pointed out. Side guides 30 are provided on the rear guide-bar 18 and guides 31 on the guide-bar 22 of the carriage to prevent 30 lateral displacement of the pack of sheets relatively to the platen. The various webs are joined by the folds 24 at their side edges, as above stated, to prevent cumulative creep of the sheets relatively to each other, 35 which occurs when feeding a pack of separated sheets around the platen.

The webs are usually provided with printed forms, thus forming superposed sets. After a set of forms has been typed, it is desirable 40 to shift the carbon-sheets relatively to the pack of webs to a new set of forms, before the typed forms are severed. To enable this to be done, the platen is mounted in a frame 35, which may be swung about a shaft 45 36 on the typewriter-carriage to raise the platen, and thus permit the webs 21 to be straightened out, so that the carbon-sheets may be freely moved rearwardly by pushing the carbon-carriage 27 by means of a handle 50 37. During the carbon-displacing operation, the pack of sheets may also be drawn forwardly until arrested by the usual stop or gage (not shown) with which the leading edge of the typed forms may engage so as to 55 position the typed forms at their tearing off positions. After the carbons have been displaced and the forms gaged, the platen may be lowered to its typing position and the typed forms may then be severed from the 60 pack by means of the knife 23.

In the patent to Jesse A. B. Smith, No. 1,206,765, dated November 28, 1916, there are provided slitting devices on the carbon-holders to sever the sheets along their side edges 65 as the carbon-carriage is moved rearwardly

during a carbon-displacing operation. These devices, although very effective in severing the sheets, leave the sheets with ragged edges, which, in practice, have been found objectionable.

Instead of slitting the sheets, I provide means to trim the side edges thereof, or, in other words, cut away the folds in the form of shavings 40, in order to sever the sheets, so that they may present smooth edges after 70 the severing operation. To this end, there may be provided a rotary cutter 41 at each side of the pack 20 of sheets, the cutters being secured to a shaft 42 mounted in ears 43 of brackets 44 extending rearwardly from 80 the carbon-carriage 27, the distance between the cutters being slightly less than the width of the pack of sheets, so that the edges of the pack may be trimmed as the carbon-carriage is moved rearwardly during the carbon-displacing operation. The cutters 41 may be 85 opposed by another set of co-operating cutters 45 mounted beneath the pack of sheets and secured to a shaft 46 also supported by the ears 43 of brackets 44.

The cutters may be driven so that their peripheral speed may be greater than their bodily movement. For this purpose, the two shafts 42 and 46 are connected to each other by gears 50 and 51, and the lower shaft 90 46 has secured thereto a pinion 52 meshing with a rack 53 fixed to one of the side bars 16 of the rearward extension by suitable brackets 54. It will be seen that the rack 53 may be disposed above or below the pinion 52 as indicated in Figures 1 and 5, respectively, to cause the cutters to rotate towards or away from the webs.

To guide the pack of sheets horizontally to the cutters 41 and 45, there may be provided an upper guide-bar 55 and a lower guide-bar 56, between which the pack is fed, the lower guide-bar 56 being secured to extensions 57 of the brackets 44 on the carbon-carriage. The upper guide-bar 55 is held 10 in place by screws 58 extending upwardly from the lower guide-bar 56, and is pressed against the lower guide-bar by suitable springs 60, the tension of which may be adjusted by nuts 61. To prevent the pack of 11 sheets from moving sidewise at the cutters, there may be provided side guides 62, which may be formed on rearward projections 63 of the lower guide-bar 56.

To prevent the shavings 40 of the edges of the webs from coming into contact with the gears 50 and 51, there may be provided a guard 64 to guide the shavings outwardly between the rack 53 and side bar 16 of the table 13.

In a modified form of the invention, the upper rotary cutters 41 may be opposed by vertical edges 65 on the lower guide-bar 56, as indicated in Figure 6. In this form, the guide-bar has extensions 56a at each side, 130

by which it may be directly connected with the carbon-carriage 27, and a side-guide 62^a extends upwardly at each end of the bar 56. The shaft 42 is supported in brackets 62^b on ears 62^c extending inwardly from the upper edges of the side-guides 62^a.

Variations may be resorted to within the scope of the invention, and portions of the improvements may be used without others.

10 Having thus described my invention, I claim:

1. In a typewriting machine comprising a platen over which a pack of work-sheets may be fed, a carriage movable lengthwise 15 of said pack, and a cutter on said carriage and rotatable by movement of the carriage to sever the sheets at one edge of the pack.

2. In a typewriting machine comprising a platen over which a pack of work-sheets 20 may be fed, a rotatable cutter adjacent an edge of said pack, means to move said cutter lengthwise of said pack, and means to rotate said cutter during such movement to trim off said edge.

25 3. In a typewriting machine, the combination of a platen over which may be fed a fan-fold pack and interleaved carbon-sheets, means, including a carbon-sheet carrier, to effect a relative shifting of the carbon-sheets and the pack, a circular cutter rotatable to shave off the edge of the pack to sever the sheets, and means rendered effective by such shifting to actuate said cutter.

4. In a typewriting machine comprising 35 a platen over which may be fed a pack of work-sheets joined at their edges, a carriage movable lengthwise of said pack, means to sever the work-sheets at one edge of the pack, said severing means including cutting blades mounted on said carriage at opposite faces of the pack, and gearing actuatable by movement of the carriage to operate said blades.

5. In a typewriting machine comprising 45 a platen over which a pack of work-sheets may be fed, a carriage movable lengthwise of said pack, two oppositely-disposed cutters on said carriage to sever the sheets by cutting off an edge of the pack, gearing to cause said cutters to rotate simultaneously, and means actuatable by movement of said carriage to cause the peripheral speed of said cutters to be greater than their bodily movement.

55 6. In a typewriting machine comprising a platen over which a pack of work-sheets may be fed, a carriage movable lengthwise of said pack, a rotatable cutter on said carriage to sever the sheets, a second rotatable cutter on said carriage and oppositely disposed to the first-mentioned cutter to assist in severing said sheets, and cutter-rotating means actuatable by movement of the carriage as the carriage is moved lengthwise of the pack.

7. In a typewriting machine comprising a platen over which a pack of work-sheets may be fed, a carriage movable lengthwise of said pack, a rotatable cutter on said carriage to sever said sheets, and a rack geared 70 to said cutter to cause the rotation of said cutter as it is moved bodily lengthwise of said pack.

8. In a typewriting machine comprising a platen over which a pack of work-sheets 75 may be fed, a carriage movable lengthwise of said pack, a rotatable cutter on said carriage to sever said sheets, and a rack geared to said cutter to cause the peripheral speed of said cutter to be greater than the speed 80 of said carriage when the latter is operated.

9. In a typewriting machine comprising a platen over which a pack of work-sheets may be fed, a rotatable cutter, means to move said cutter lengthwise of said pack to 85 sever said sheets, and means to cause the peripheral speed of said cutter to be greater than its bodily speed.

10. In a typewriting machine, the combination of a platen over which a fan-fold 90 pack of work-sheets may be fed, a cutter, means to move said cutter bodily along one edge of said pack, and means actuatable by such movement of said cutter to rotate said cutter to shave off the adjacent edge of the 95 pack to sever the sheets.

11. In a typewriter machine, the combination of a platen over which a pack of sheets may be fed, said sheets being folded 100 at their side edges, a plurality of cutters adjacent said side edges, means for moving said cutters lengthwise of said pack, and gearing actuatable by movement of said cutter-moving means to rotate said cutters to sever the sheets at their folded edges. 105

12. In a typewriting machine comprising a platen over which a pack of work-sheets may be fed, a carriage movable lengthwise of said pack, a rotatable cutter on said carriage to sever the sheets, a rotatable cutter 110 oppositely disposed to the first-mentioned cutter to assist in severing the sheets, said cutters being geared to each other, and means to cause the peripheral speed of said cutters to be greater than their bodily movement. 115

13. In a typewriting machine, the combination of a platen over which a pack of work-sheets may be fed, a carriage movable 120 lengthwise of said pack, a rotatable cutter on said carriage to sever the sheets, cutter-rotating means actuatable by movement of said carriage, and two guide-bars on opposite sides of the pack to guide it to said cutter. 125

14. In a typewriting machine comprising a platen over which a pack of work-sheets may be fed, a rotatable cutter, means for moving said cutter lengthwise of said pack 30 to sever said sheets, means actuatable by the

- movement of said moving means to rotate said cutter, and means to guide the pack to said cutter.
15. In a typewriting machine comprising a platen over which a pack of work-sheets, joined at their edges, may be fed, a carriage movable lengthwise of said pack, two guide-bars mounted on the carriage to engage the pack on opposite faces, a rotatable cutter on one of said guide-bars to sever the sheets, side-edge guides mounted on one of said guide-bars, and means, including a rack geared to said cutter, to cause said cutter to rotate as it is moved bodily lengthwise of said pack.
16. In a typewriting machine comprising a platen over which a pack of work-sheets, joined at their edges, may be fed, a carriage movable lengthwise of said pack, two guide-bars mounted on the carriage to engage the pack on opposite faces, a rotatable cutter on one of said guide-bars to sever the sheets, and means, including a rack geared to said cutter, to cause said cutter to rotate as it is moved bodily lengthwise of said pack.
17. In a typewriting machine comprising a platen over which a pack of work-sheets may be fed, a rotatable cutter, means to move said cutter lengthwise of said pack to sever said sheets, means to cause the peripheral speed of said cutter to be greater than its bodily speed, and means to guide the pack to said cutter.
18. In a typewriting machine, the combination of a platen over which a pack of sheets may be fed, said sheets being folded at their side edges, a plurality of cutters movable lengthwise of said pack, gearing to rotate said cutters as they are moved bodily to sever the sheets at their folded edges, and guiding means to conduct the pack to said cutters.
19. In a typewriting machine, the combination of a platen over which a fan-fold web may be fed, a horizontally-disposed guide for said web, two rotatable cutters, disposed above said guide, one near each side edge of said web, a shaft to connect said cutters with each other, a carriage upon which said cutters are mounted and by which they may be moved lengthwise of said web, a rack adjacent to one edge of the carriage and relatively to which the carriage is movable, means connecting said shaft with said rack so that the cutters may be rotated when the carriage is moved lengthwise of said web, and means to guide the severed edge at the edge of the web adjacent the rack so as to guide the severed edge past said rack.
20. An attachment for a carbon-carriage of a fan-fold machine, comprising a bar extending across said carriage beneath the path of a fan-fold web in the machine, a second bar, to engage the upper side of the fan-fold web, mounted on the first bar and yieldingly urged toward the first bar, an edge-trimming device comprising two opposed blades at each edge of the web, and means actuatable by the carriage to operate said blades.
21. In a typewriting machine of the fan-fold type, in combination, a reciprocable carbon-carriage, means on said carriage for trimming the edges of a fan-fold web passing through the carriage, and actuating means for the trimming means including a rack extending longitudinally of the web.
22. In a typewriting machine, the combination of a platen over which a pack of work-sheets may be fed, two rotatable cutters, one near each side edge of the pack, two opposing cutters, all of said cutters being connected to rotate simultaneously and being movable together longitudinally of the pack, and means for driving said cutters when so moved along the pack.
23. An attachment for a carbon-carriage of a fan-fold machine, comprising a bar extending across said carriage beneath the path of a fan-fold web in the machine, a second bar, to engage the upper side of the fan-fold web, mounted on the first bar and yieldingly urged toward the first bar, an edge-trimming device comprising two opposed blades at each edge of the web, side-edge guides for said web mounted on the first bar, and means actuatable by movement of the carriage to operate said blades.
24. In a typewriting machine, the combination of a platen over which a fan-fold pack of work-sheets may be fed, two cutters, one near each side edge of the pack, a shaft to which said cutters may be secured, two opposing cutters associated with said first-mentioned cutters, said shafts having a geared connection, and a rack to drive the gears to rotate said cutters.
25. In a typewriting machine, the combination of a platen over which a fan-fold web may be fed, a horizontally-disposed guide for said web, two rotatable cutters disposed above said guide, one near each side edge of said web, a shaft to connect said cutters with each other, means to move said cutters lengthwise of said web, and means to rotate said cutters.
26. In a typewriting machine, the combination of a platen over which a fan-fold web may be fed, a horizontally-disposed guide for said web, two rotatable cutters, disposed above said guide, one near each side edge of said web, a shaft to connect said cutters with each other, a carriage upon which said cutters are mounted and by which they may be moved lengthwise of said web, a rack relatively to which said carriage may be moved, and means connecting said shaft with said rack so that the

cutters may be rotated when the carriage is moved lengthwise of said web.

27. In a typewriting machine, the combination of a platen over which a fan-fold pack of sheets may be fed, cutters to shave off the edges of said pack, driving means for said cutters at one edge of the pack and means at the edge of the pack adjacent said driving means to guide the shavings so as to avoid interference thereof with the driving means.

28. In a typewriting machine comprising a platen over which may be fed a pack of work-sheets joined at their edges, and a reciprocal carbon-carrier to retract carbon-sheets interleaved between said work-sheets, in combination, co-operative rotary cutters mounted on said carbon-carrier to engage the opposite faces of the pack adjacent one edge thereof, gearing connecting said cutters to cause movement of the adjacent effective parts of the cutters in the same direction, and means to so rotate the cutters during the rearward movement of the carbon-carrier that the direction of movement of said adjacent effective parts of the cutters will be opposite that in which the carbon-carrier is moving.

29. In a typewriting machine comprising a platen over which may be fed a pack of work-sheets joined at their edges, and a reciprocal carbon-carrier to retract carbon-sheets interleaved between said work-sheets, in combination, co-operative rotary cutters mounted on said carbon-carrier to engage the opposite faces of the pack adjacent one edge thereof, gearing connecting said cutters to cause movement of the adjacent effective parts of the cutters in the same direction, and means to so rotate the cutters during the rearward movement of the carbon-carrier that the direction of movement of said adjacent effective parts of the cutters will be opposite that in which the carbon-carrier is moving, and the peripheral speed of said cutters will be greater than the speed of the carbon-carrier.

30. In a typewriting machine comprising a platen over which may be fed a pack of work-sheets joined at their edges, and a reciprocal carbon-carrier to retract carbon-sheets interleaved between said work-sheets, in combination, co-operative rotary cutters mounted on said carbon-carrier to engage

the opposite faces of the pack adjacent one edge thereof, means connecting said cutters to cause movement of the adjacent effective parts of the cutters in the same direction, and means to so rotate the cutters during the rearward movement of the carbon-carrier that the direction of movement of said adjacent effective parts of the cutters will be opposite that in which the carbon-carrier is moving.

31. In a machine for typing upon a continuous fan-fold work-web, in combination, a revoluble platen, a carbon-carrier reciprocable toward and from the platen to control the carbon-sheets interleaved with the plies of said work-web, co-operative rotary cutters mounted on said carbon-carrier to engage the opposite face of the web adjacent one edge thereof, gearing connecting said cutters to cause movement of the adjacent effective parts of the cutters in the same direction, and means to so rotate the cutters during rearward movement of the carbon-carrier that the direction of movement of said adjacent effective parts of the cutters will be the same as that in which the carbon-carrier is moving.

32. In a typewriting machine, in combination, a platen around which a fan-fold work-web may be fed, two rotatable cutters, one near each side of the web, and means operating during relative movement of the web and cutters longitudinally of the web, to rotate the cutters to trim the sides of the web.

33. In a typewriting machine, the combination with a carbon-carrier and a set of carbons carried thereby, of a continuous fan-fold web interleaved with the carbons, a rotary web-trimmer for trimming the sides of the web, and means operated by relative movement of the trimmer and the web to rotate the trimmer to trim the web.

34. In a typewriting machine, the combination of a platen around which a fan-fold work-web may be fed, two rotatable cutters, one near side of the web, means operating during relative movement of the web and cutters longitudinally of the web to rotate the cutters to trim the sides of the web, and non-rotatable shearing members co-operating with the rotatable cutters in trimming the web.

JOHN WALDHEIM.
